UNITED STATES PATENT OFFICE.

OSWALD JACKSON, OF CARROLLTON, ILLINOIS.

VALVE-GEAR FOR ENGINES.

SPECIFICATION forming part of Letters Patent No. 691,384, dated January 21, 1902.

Application filed January 26, 1901. Serial No. 44,795. (No model.)

To all whom it may concern:

Be it known that I, OSWALD JACKSON, residing in Carrollton, in the county of Greene and State of Illinois, have invented a new and useful Improvement in Valve-Gear for Engines, of which the following is a description, reference being had to the accompanying drawings, which are a part of this specification.

10 My invention has relation to improvements in valve-gear for engines, being adaptable to any common slide-valve of a stationary, traction, or locomotive engine.

The primary object of the invention is to 15 provide an improved construction whereby an actuating agent may be automatically cut off from the cylinder as the load on the engine may vary.

A further object is to provide for admitting 20 and cutting off the steam instantly.

A further object is to provide an improved construction whereby the engineer is enabled 25 to cut off the steam at any part of the stroke and thereby permit said steam to work expansively for the remainder of the stroke without changing any part of the gear and in marine engines enabling the engineer to run one-half, three-fourths, or any speed he desires.

With the above objects and other incidental objects in view the invention consists of 30 the devices and parts or their equivalents as hereinafter set forth.

In the accompanying drawings, Figure 1 is 35 a plan view of the engine. Fig. 2 is a section on the line 2 2 of Fig. 1. Fig. 3 is a section through the valve-casing. Fig. 4 is a detail of one of the governor-weights and allied parts. Fig. 5 is a cross-section through the saddle-plate, and Fig. 6 is a view of a modified form of valve-operating mechanism.

Referring to the drawings, the letter *a* indicates a valve-casing of an ordinary engine mechanism into which steam is admitted either from the top or side, as desired. This 45 valve-casing is provided in its bottom with the usual channels *b* and *c*, respectively, which lead to the cylinder below, (not shown,) and with an exhaust-channel *d*. Within the valve-casing is the usual valve *e*, which is 50 adapted to connect either of the channels leading to the cylinder with the exhaust-channel. Extending from the valve and through one

end of the valve-casing is a valve-rod *f*. Passing through the outer end of this valve-rod is a pivot-bolt *g*, said bolt carrying an antifriction-roller *h*, which works in a slot *i*, formed in a plate *j* for the purpose of keeping the valve-rod in a central position. The bolt *g* also passes loosely through a rod *k*. Extending through the outer end of the rod *k* is a bolt *l*, said bolt passing through an elongated slot *m*, formed in a saddle-plate *n*, said slot being preferably curved. The lower end of the bolt *l* passes through an elongated slot *o*, formed in a lever *p*, said lever being pivoted at one 65 end, as indicated by the letter *q*. The lower end of the bolt *l*, which projects below the lever *p*, has a nut *r* screwed thereon to prevent the withdrawal of the bolt from the slot. The free end of the lever *p* is in the form of a 70 fork, as indicated by the letters *s*, and the ends of the arms of the fork carry antifriction-rollers *t t*.

The letter *u* indicates the ordinary crank-shaft of an engine mechanism, said shaft having 75 mounted on one end thereof the usual crank-disk *v*, which is connected to the piston-rod (not shown) of a cylinder by means of the usual pitman. (Also not shown.) As is well understood in this class of mechanism, 80 the reciprocation of the piston in the cylinder causes the rotation of the crank-shaft.

Surrounding a medial portion of the crank-shaft is a cam *w*. This cam is pivoted on the shaft, preferably by means of threaded studs 85 *x x*. The inner ends of these studs are conical and engage conical recesses at diametrically opposite points of the shaft, (see Fig. 2,) while their outer ends are secured to diametrically opposite points of the inner 90 circumference of the cam. By thus mounting the cam upon the shaft said cam may be readily turned upon the pivots *x* to a more or less oblique plane. Nuts *y y* engage the threads of the screw-studs and when turned 95 are adapted to adjust the studs, so as to compensate for any wear at the conical ends of said studs.

The cam *w* is of peculiar shape, (best illustrated in Figs. 1 and 2)—that is to say, it consists of the two portions *z z*, which are on a plane concentric to the axis of the crank-shaft, but considerably removed from each other in the direction of the length of the

shaft, and the connecting portions 11, which are on diagonal planes across the axis of the crank-shaft. The arms of the fork *s* are adapted to straddle the portions *z z* and 11 of 5 the cam, and the antifriction-rollers *t t* of said arms bear against opposite sides of said portions of the cam. Around the inner circumference of the cam is a flange 2, which projects at right angles to the portions *z z* and 11. 10 From opposite points of the crank-shaft extend short posts 3 3, to which are pivotally connected governor-arms 4 4, the inner ends of said arms being formed or provided with weights 5 5, the inner sides of said weights 15 preferably conforming to the contour of the shaft. Pivotally connected to the weights and extending therefrom in directions opposite to the directions in which the arms 4 extend are links 6 6. The other ends of these 20 links are pivotally connected to diametrically opposite points of the inner side of the flange 2 of the cam. Projecting from each weight are lugs 7 7, and to the ends of these lugs are connected coiled springs 8 8. The 25 ends of these springs which project beyond the lugs are threaded to receive nuts 9 9. The opposite ends of the springs are connected to collars 10 10, which are mounted on the pivot-studs *x*. It is obvious that by turning the 30 nuts the tension of the springs may be readily regulated.

Pivoted to diametrically opposite points of the crank-shaft are cushion-pots in the form of small cylinders 11 11. These pots are intended to be filled with some suitable resisting agent, preferably a liquid, such as glycerin or oil of any kind. A piston 12 is adapted to reciprocate in each cylinder, and each piston is provided with a small aperture 13. 35 To each piston is also connected a piston-rod 14, said rod extending outwardly through one end of the cylinder and being pivotally connected at its outer end to an arm 15, projecting from the inner flange.

40 Mounted slidably on the crank-shaft is a flanged collar 16. The sliding movement is preferably obtained by providing the collar with a key 17, which engages an elongated groove 18 in the crank-shaft.

45 The numeral 19 indicates a medially-pivoted lever. One end of this lever is forked, and the arms of the fork engage diametrically opposite points of the groove of the collar, the extremities of the arms of the fork 50 being preferably provided with antifriction-rollers 20. The collar 16 has extending from one side thereof a projection 21, which is in the form of a wedge and is adapted when the collar 16 is moved in one direction to slide 60 under the lug extending from the flange 2, and to which lug one of the links 6 is connected.

In explanation of the operation of the invention it is to be stated that when the shaft 65 *u* is revolved the cam *w* is of course revolved therewith. As this cam revolves when one of the inclined portions 1 thereof is brought

into contact with the arms of the fork *s*, the lever *p* is turned on its pivot, and as this lever is connected to the rod *k* and said rod *k* in 70 turn to the valve-rod *f* the pivot-bolt is forced to travel in the slot *m*. This will actuate the valve-rod *f* and cause said rod to move the valve *e* in a direction to open either of the channels *b* or *c*, in accordance with the direction of the movement of the valve-rod. Now when the cam has rotated sufficiently far to bring either of the surfaces *z z* into contact with the arms of the fork *s* no movement whatever is imparted to the lever *p*, and this 80 occurs at the time either one or the other of the channels *b* or *c* is open, the said channel receiving the full head of steam during the time the portion *z* is in engagement with the arms of the fork *s*. When the portion *z* 85 of the cam is rotated out of engagement with the fork-arms and said fork-arms thereby brought into engagement with the other inclined portion 1 of the cam, this inclined portion will turn the lever *p* in an opposite direction to gradually open the other channel, and when the cam is revolved sufficiently far to bring the other portion *z* into engagement with the arms of the fork *s* said other channel is opened fully and is kept open until 90 95 said portion *z* rides out of engagement with the fork-arms, and so on throughout the rotation of a cam. Heretofore in all valve-gears operated by eccentrics and yokes the admission of steam into the cylinder is gradual and the cut-off of steam also gradual, with the result that the channel or port is 100 only open to its full extent for the smallest possible length of time, and of course the piston-head is only obtaining the full pressure 105 of steam from the boiler during the short period of time this channel or port is fully open. It will be seen, however, that by my construction the full head of steam is permitted to enter the cylinder for a considerable period 110 of time, and thereby the full pressure of the steam is utilized for a much longer period of time than has heretofore been the case. If during the operation the speed of the engine 115 becomes too great, the governor-weights will 120 fly outwardly, and this movement of the weights by reason of the connection of the links 6 with the cam will cause said cam to be automatically tilted to a less oblique position against the contrary force exerted by 125 the springs 8, and when thus tilted the throw of the lever *p* will be lessened, and consequently the channels *b* and *c* will not be fully opened, and which of course will have the effect of reducing the speed of the engine. 130 When the speed falls to a certain point, the weights will again fly inwardly, and consequently the cam will be tilted back toward its more oblique position. As previously stated, by adjusting the nuts 9 the tension of 135 the springs 8 may be regulated so as to offer greater or less resistance to the governor-weights flying outwardly. When the cam is tilted in the manner explained, the piston-

rods 14 are necessarily moved in and out, and this has the effect of reciprocating the pistons in the cushion-pots 11. As these pistons move the oil is forced through the small aperture 13 in each piston from one side of the piston to the other in the alternate reciprocation of the piston, which of course insures a steady movement. Whenever the engineer desires to cut off the steam at any part 5 of the stroke in order that the steam may work expansively for the remainder of the stroke without changing any part of the valve-gear, the lever 19 is grasped and turned in a direction to cause the flanged collar 16 to 10 move toward the cam. As said collar thus moves the wedge 21 thereof acts upon the cam, and thus raises the cam to a less oblique position. This raising of the cam to a less 15 oblique position by manipulation of the engineer will be found of particular advantage 20 in marine engines, as the engineer is enabled to go one-half, three-fourths, or any speed he wishes. Of course when the lever 19 is turned in the opposite direction to that first explained 25 the springs 8 will turn the cam back to a more oblique position.

While the mechanism for turning the cam to a less oblique position by manipulation of the engineer which is shown in the accompanying drawings and just described is the preferred arrangement for that purpose, yet I do not wish to be understood as limiting myself specifically thereto, as any other equivalent mechanism for accomplishing that purpose 30 may be provided without departing from the spirit and scope of my invention. I also wish it understood that my improvement may be employed in connection with mechanism operated by an actuating agent other than 35 steam—as, for instance, gas, air, and the like. I furthermore do not wish to be understood as restricting myself to the particular form of connection between the lever *p* and the valve *e*, as various forms of connection may 40 be employed without departing from the spirit and scope of my invention, and in Fig. 6 I have illustrated a form of connection which is applicable to reversible engines. In the connection illustrated in the other figures of 45 the drawings such form of connection is only applicable to non-reversible engines. In the modified form for reversible engines illustrated in said Fig. 6 the lever *p* instead of being pivoted at its end, as shown in the other figures of the drawings, is pivoted at a 50 medial point on a plate 22. The end of the lever opposite to the forked end thereof is pivoted at the point 23 to a link 24. The center of the slot *m* of the saddle-plate *n* is 55 in line with the valve-rod *f*, and said plate instead of being fixed, as in the other figures of the drawings, is pivoted at the point 25. Pivoted to one end of the saddle-plate is a link 26, and to the end of this link is pivoted 60 a lever 27, which carries a dog working over the toothed edge of a segment 28. By manipulating the lever 27 it is obvious that the en-

gineer can change the course of the bolt *l*, which bolt passes through the elongated slot *m*, and consequently the course of the valve *e* is thereby changed. It will be understood, of course, that the bolt *l*, which passes through the slot *m* and connecting-rod *k*, also passes through the link 24.

What I claim as my invention is—

1. In a valve-gear, the combination of a valve-casing, a valve therein for regulating the channels or ports leading to and from the cylinder, a valve-rod extending from the valve, a connecting-rod pivoted to the valve-rod, a plate provided with an elongated slot, a crank-shaft, a lever actuated by the crank-shaft, said lever being pivoted at one end, and a bolt extending through the slot of the plate and connected to a medial point of the lever and to the end of the connecting-rod. 75

2. In a valve-gear, the combination of a valve-casing, a valve therein for regulating the channels or ports leading to and from the cylinder, a valve-rod extending from the valve, a connecting-rod pivoted to the valve-rod, a plate provided with a curved, elongated slot, a crank-shaft, a lever actuated by the crank-shaft, said lever being pivoted at one end and provided at a medial point with an elongated slot, and a bolt connected to the end of the connecting-rod and passing through the curved slot of the plate and through the slot of the lever and held against withdrawal from said slot of the lever. 95

3. In a valve-gear, the combination of a valve-casing, having a valve therein for regulating the channels or ports leading to and from the cylinder, a crank-shaft, a cam mounted at an obliquity upon the crank-shaft; a pivoted lever provided at one end with a fork, the arms of said fork engaging opposite faces of the cam, whereby the lever is caused to be turned on its pivot as the cam is revolved, a connection between the lever and the valve, and governor mechanism adapted to act on the cam in order to throw said cam to a more or less oblique position dependent upon the speed of the engine, and thereby regulate the throw of the valve. 105

4. In a valve-gear, the combination of a valve-casing having a valve therein for regulating the channels or ports leading to and from the cylinder, a crank-shaft, a cam mounted at an obliquity upon the crank-shaft, a pivoted lever provided at one end with a fork, the arms of said fork carrying antifriction-rollers which engage the opposite faces of the cam, whereby the lever is caused to be turned on its pivot as the cam is revolved, a connection between the lever and the valve, and governor mechanism adapted to act on the cam in order to throw said cam to a more or less oblique position dependent upon the speed of the engine, and thereby regulate the throw of the valve. 125

5. In a valve-gear, the combination of a valve-casing having a valve therein for regulating the channels or ports leading to and

from the cylinder, a crank-shaft, a cam mounted upon the crank-shaft in such manner as to be turned to a more or less oblique position, mechanism between the cam and the 5 valve-rod and adapted to be actuated by the cam as said cam is revolved to thereby cause the actuation of the valve, and governor mechanism adapted to act on the cam and automatically throw said cam to a more or less 10 oblique position dependent upon the speed of the engine, and thereby automatically regulate the throw of the valve.

6. In a valve-gear, the combination of a valve-casing having a valve therein for regulating the channels or ports leading to and from the cylinder, a crank-shaft, a cam mounted upon said shaft in such a manner as to be turned to a more or less oblique position, said cam provided with two portions which 15 are concentric with the axis of the crank-shaft but a distance removed from each other in the direction of the length of the shaft, and with two connecting portions disposed in planes oblique to the axis of the shaft, mechanism between the cam and the valve and adapted to be acted upon by said portions of the cam as the cam is revolved to thereby cause an actuation of the valve, and governor mechanism adapted to act on the cam 20 25 30 in order to throw said cam to a more or less oblique position dependent upon the speed of the engine, and thereby regulate the throw of the valve.

7. In a valve-gear, the combination of a valve-casing having a valve therein for regulating the channels or ports leading to and from the cylinder, a crank-shaft, a cam mounted upon the crank-shaft in such a manner as to be turned to a more or less oblique position, said cam provided with two portions which are concentric to the axis of the crank-shaft but a distance removed from each other in the direction of the length of the said shaft, and with two connecting portions disposed in 35 40 45 planes oblique to the axis of the shaft, a lever provided with a forked end, the arms of said fork adapted to be acted upon by the said portions of the cam as the cam is revolved, connections between said lever and the valve, and governor mechanism adapted 50 to act on the cam in order to throw said cam to a more or less oblique position dependent upon the speed of the engine, and thereby regulate the throw of the valve.

8. In a valve-gear, the combination of a valve-casing having a valve therein for regulating the channels or ports leading to and from the cylinder, a crank-shaft, a cam mounted thereon in such a manner as to be turned to a more or less oblique position, a governor-arm pivotally connected to the crank-shaft, a governor-weight at the end of said arm, a 55 link pivotally connected at one end to the weight and at its opposite end to the cam, and mechanism between the cam and the valve and adapted to be actuated by the cam

as said cam is revolved to thereby cause the actuation of the valve.

9. In a valve-gear, the combination of a valve-casing having a valve therein for regulating the channels or ports leading to and from the cylinder, a crank-shaft, a cam mounted thereon in such a manner as to be turned to a more or less oblique position, governor-arms pivotally connected to the crank-shaft, 70 governor-weights at the ends of the governor-arms, links, each pivotally connected at one end to a governor-weight and at its opposite end to the cam, and mechanism between the cam and the valve, and adapted to be actuated by the cam as said cam is revolved to thereby cause the actuation of the valve.

10. In a valve-gear, the combination of a valve-casing having a valve therein for regulating the channels or ports leading to and 80 from the cylinder, a crank-shaft, a cam mounted thereon in such a manner as to be turned to a more or less oblique position, a governor-arm pivotally connected to the crank-shaft, a spring-tensioned governor-weight at the end 85 of the governor-arm, a link pivotally connected at one end to the governor-weight but at its opposite end to the cam, and mechanism between the cam and the valve and adapted to be actuated by the cam as said cam is revolved, and thereby cause the actuation of the valve.

11. In a valve-gear, the combination of a valve-casing having a valve therein for regulating the channels or ports leading to and 90 from the cylinder, a crank-shaft, a cam mounted thereon in such a manner as to be turned to a more or less oblique position, a governor-arm pivotally connected to the crank-shaft, a spring-tensioned governor-weight at the end 95 of the governor-arm, means for adjusting the spring tension, a link pivotally connected at one end to the governor-weight and at its opposite end to the cam, and mechanism between the cam and the valve, and adapted to be actuated by the cam as said cam revolves to thereby cause the actuation of the valve.

12. In a valve-gear, the combination of a valve-casing having a valve therein for regulating the channels or ports leading to and 100 from the cylinder, a crank-shaft, a cam mounted thereon in such a manner as to be turned to a more or less oblique position as the speed of the rotation of the shaft changes, mechanism between the cam and the valve and adapted to be actuated by the cam as the cam revolves, to thereby cause the actuation of the valve, a cushion-pot pivoted to the crank-shaft and adapted to contain a resisting agent, a piston in the pot and provided with an aperture, a piston-rod extending from the pot, and a connection between said rod and the cam.

13. In a valve-gear, the combination of a valve-casing having a valve therein for regulating the channels or ports leading to and 110 from the cylinder, a crank-shaft, a cam

mounted thereon in such a manner as to be turned to a more or less oblique position as the speed of rotation of the shaft changes, mechanism between the cam and the valve and adapted to be actuated by the cam as said cam revolves and thereby cause the actuation of the valve, cushion-pots pivoted to the shaft and adapted to contain a resisting agent, pistons in the pots, each provided with an aperture, piston-rods extending from the pots, and a connection between each piston-rod and the cam.

ed thereon in such a manner as to be turned 30 to a more or less oblique position, mechanism between the cam and the valve and adapted to be operated by the cam as said cam is revolved, and thereby cause the actuation of the valve, a slidable collar on the shaft, said 35 collar provided with a projection adapted to act on the cam, and means for causing a sliding movement of the collar to thereby cause the projection thereof to throw the cam to a more or less oblique position.

14. In a valve-gear, the combination of a valve-casing having a valve therein for regulating the channels or ports leading to and from the cylinder, a crank-shaft, a cam mounted thereon in such a manner as to be turned to a more or less oblique position, mechanism between the cam and the valve and adapted 40 to be operated by the cam as said cam is revolved, and thereby cause the actuation of the valve, and mechanism under the manual control of the operator, and constructed when operated to cause the cam to be turned to a more or less oblique position.

15. In a valve-gear, the combination of a valve-casing having a valve therein for regulating the channels or ports leading to and from the cylinder, a crank-shaft, a cam mount-

ed thereon in such a manner as to be turned 30 to a more or less oblique position, mechanism between the cam and the valve and adapted to be operated by the cam as said cam is revolved, and thereby cause the actuation of the valve, a slidable collar on the shaft, said 35 collar provided with a projection adapted to act on the cam, and means for causing a sliding movement of the collar to thereby cause the projection thereof to throw the cam to a more or less oblique position.

16. In a valve-gear, the combination of a valve-casing, a valve therein for regulating the channels or ports leading to and from the cylinder, a valve-rod extending from the valve, a connecting-rod pivoted to the valve- 45 rod, a pivoted plate provided with an elongated slot, mechanism for turning said plate on its pivot and holding it in adjusted position, a crank-shaft, a lever actuated by the crank-shaft, and a connection between the 50 lever and the connecting-rod, said connection adapted to ride in the slot of the plate.

In testimony whereof I affix my signature in presence of two witnesses.

OSWALD JACKSON.
